ELECTRICAL SOUND TRANSLATING DEVICE

Lionel B. Cornwell, New Canaan, Conn., and John F. Nielsen, Forest Hills, N. Y.

Application February 16, 1945, Serial No. 578,206

15 Claims. (CL. 179—100.41)

1

This invention relates to electrical sound translating devices of the so-called magnetic type. The invention is useful in translating mechanical motion into electrical impulses, as well as in translating electrical impulses into mechanical motion.

The invention is adapted for use as a microphone or to pick up any motion of a vibratory nature. As exemplified in the present embodiment the invention takes the form of a phonograph pickup and the following disclosure of such embodiment will be sufficient to permit those skilled in the art to understand the invention and the various uses to which it may be put.

In the usual magnetic pickup device of the prior art the magnetic forces tend to pull the armature to one pole face or the other and subject the armature to freezing to a pole piece; and the armature is likewise subject to striking the pole pieces during its operative movement. To prevent this it has been found necessary or desirable to employ rubber damper blocks. It has been attempted, without success, to make these dampers compliant enough to allow armature vibration within the desired limits of operation but stiff enough to oppose the magnetic pull and to normally center the armature in a neutral or mid position. When such damper blocks are stiff enough to effect centering of the armature poor fidelity of reproduction results, thereby requiring a compromise which results in neither a faithful reproduction nor in freedom from freezing. Additionally, the necessary stiffness of these blocks imposes upon the stylus an undesirable resistance to lateral motion, causing premature wearing of the record groove.

Another disadvantage of the prior art magnetic pickup devices resides in the fluctuation of density and reversal of flow of magnetic flux through the armature each time the stylus is oscillated through a complete cycle of movement, as by a sound record groove. This is highly undesirable because of eddy losses and hysteresis which are appreciable in view of the small mass of the armature and the relative high flux density necessary in order to attain fidelity and high output efficiency of reproduction with the use of an armature having small mass.

In sound track records of the lateral undulation type there are also present slight vertical undulations, and hence it is desirable that a stylus in following the lateral undulations also have a certain degree of freedom to follow the ancillary vertical undulations in order to faithfully reproduce the sound represented by said

5 lateral undulations and conversely it is desirable to prevent translation of the ancillary vertical vibrations into sound. Similarly, in vertical undulation type records there are also present slight lateral undulations of an ancillary nature and for similar reasons it is desirable to provide some freedom of movement of the stylus laterally while at the same time refraining from translating said ancillary undulations into sound.

10 An object of this invention is to provide a device which will overcome the above shortcomings and disadvantages and which will have the attributes above indicated.

15 Another object of the invention is to provide a device of the type described which will faithfully translate the desired sound while prohibiting undesirable noises due to extraneous electrical disturbances.

20 Another object of the invention is to provide a device adapted for universal use with records of either the lateral cut or vertical cut types.

25 The invention consists of the novel features, arrangements, construction and combination of parts embodied, by way of example, in the apparatus to be hereinafter more fully described as illustrating a present preferred form of the invention, and the invention will be more particularly pointed out in the appended claims.

30 Further and more specific objects, features and advantages of the invention will more clearly appear from the detailed description to be given following, taken in connection with the accompanying drawings in which:

35 Fig. 1 is a front elevational view of a pickup device, shown somewhat diagrammatically and on an enlarged scale.

Fig. 2 is a longitudinal sectional view taken along the line 2—2 of Fig. 1;

40 Fig. 3 is a bottom view of Fig. 1 showing further particulars as to the mounting of the armature and showing the spacing between the armature and cooperating pole pieces exaggerated for the purposes of clarity;

45 Fig. 4 is a fragmentary view of certain parts shown in Fig. 2, on a somewhat larger scale, to illustrate the parts and in a different position; and

50 Fig. 5 is a diagrammatic view in perspective illustrating a feature of the invention.

Before describing the invention in detail certain salient features will be referred to by way of introduction. An important feature of the invention resides in the use of a resiliently supported magnetic armature that cannot freeze to any of the magnetized poles and which has unre-

stricted motion throughout the maximum limits of all lateral and vertical cut phonograph records, e. g. throughout the maximum amplitude of audio frequency. This unlimited travel makes it possible to build into the resilient supporting means for the armature any value of compliance desired without danger of the permanent magnet pulling the armature into an inoperative position. Other important features of the invention are the maintenance of a relatively high density of flux flow through an armature of relatively low mass; the maintenance of a uni-directional flow of flux through the armature; and the bucking out of undesirable coil currents resulting from extraneous electrical disturbances or due to lateral motion of the stylus when reproducing vertical cut records and vice versa.

Referring to the drawings and more particularly to Fig. 1, a magnetic field is provided by a suitable magnet 10 which is polarized, as shown by the letters N and S, which in turn polarizes the laminated transformer iron pole pieces 12 and 13 having respectively corresponding branch poles N1—N2 and S1—S2. The magnet 10 is preferably a permanent magnet and is supported on a suitable frame such as 11. An armature, designated in general as 14, is disposed between the poles N1—N2 and S1—S2 so as to complete the flux path or lie in the field of influence of the flux flowing between said poles. It is noted in this connection that the poles are so disposed as to cause the magnetic flux to flow in the same direction between the poles N1, S1 and N2, S2. The armature 14 has oppositely disposed ends respectively adjacent poles N1—N2 and S1—S2 in spatial interleaved relationship therewith. In the present embodiment the armature ends take the form of two plates providing the end portions 16—17 and 18—19 which are respectively spatially interleaved with three plates provided in the poles N1—N2 and three plates provided in the poles S1—S2. It will be seen (Figs. 1, 2 and 4) that the vertical side faces of the three plates of the N1 pole are disposed in coplanar relationship with the respectively cooperating vertical faces of the three plates of the N2 pole and are spaced vertically therefrom; and similarly (Figs. 1 and 3) the vertical side faces of the three plates of the S1 pole are disposed in coplanar relationship with the respectively cooperating vertical faces of the three plates of the S2 pole and are spaced vertically therefrom. Likewise the said vertical side faces of the N1 and N2 pole plates are coplanar with the respectively cooperating vertical side faces of the S1 and S2 pole plates and are spaced laterally therefrom. In the alternative, the armature could be one piece with bifurcated ends but the illustrated structure is preferable as the entire armature mass is magnetically useful. The plate ends of the armature are spaced on all sides from the correspondingly adjacent poles with a clearance of approximately .002" to allow a free motion vertically or a rocking motion around an imaginary center C as an axis. The mounting of the armature, to be more particularly described following, and the disposition of the parts is such that neither the vertical nor the rocking motion can bring the armature into contact with the poles N1—N2 or S1—S2, within the limits of movement of the armature corresponding to range of audio frequency; thereby eliminating all possibility of freezing.

From the foregoing it will be seen that the overlapping area of the armature and poles is

varied in accordance with armature movement, but within the limits of operative movement the interleaving relationship is always present. This provides a substantially constant air gap length and a variable air gap area and is one of the important features of the present invention. This principle is diagrammatically illustrated in Fig. 5 wherein a plate 20 is disposed between a pair of plates 21—22 in spatial interleaved relationship and is adapted for relative movement from the full line position to the dotted line position. Assuming that magnetic flux is passing between the plate 20 and plates 21—22, the magnetic air gap between the plate 20 and the plates 21—22 in a direction normal to the plates is constant at all times. Flux modulation is obtained by variation in the area of coupling and is maximum when plate 20 is in the position indicated by the broken lines and is minimum when the plate 20 is in the position indicated by solid lines. Assuming that with the constant gap of .002" the flux density is 8,000 lines per square inch and the total flux area in the solid line position to be .040 square inch, the resultant minimum flux will be 320 lines per square inch. However, with the plate 20 in the broken line position the maximum area of coupling is provided and assuming this to be one square inch, the maximum flux of 8,000 lines per square inch is provided. Variations between the minimum of 320 lines and the maximum of 8,000 lines are obtained by the variation of the area of coupling.

The armature 14 is held in correct position with respect to the poles N1—N2 and S1—S2 by a flat ribbon spring 23, the inner end of which is rigidly secured to the frame 11 and the outer end of which carries secured thereto the plates which comprise the armature 14. A stylus 24 is suitably secured to the armature 14 for movement therewith. In the present embodiment the stylus, which is the means for transmitting mechanical motion to or from the armature, is provided with a base 24' rigidly secured to the spring, as by riveting. A loop of fine wire 25 is looped over the stylus 24 and its ends are securely anchored close together to the frame 11 to provide a brace serving to hold the stylus against the frictional force created by the record as it slides under the stylus in the direction indicated by the arrow D (Fig. 2); thus insuring retention of the stylus in a vertical position relative to the longitudinal direction D while permitting lateral motion.

The pickup assembly is so balanced as to present a pressure, of a predetermined value, on the record. The invention has been successfully operated with fidelity of reproduction employing predetermined pressures at least as low as 20 grams and as high at least as 40 grams. The pressure may be varied in accordance with the record material employed and the degree of external vibrations present; in present practice the pressure of 30 to 35 grams is desirable. This pressure when applied pushes the armature into the position as shown in Figures 2 and 3 putting the spring under the required tension necessary to overcome the inertia of the armature and stylus when vibrating vertically over the frequency range at the maximum amplitude cut on vertical records. Devices made in accordance with the invention function with a high degree of uniformity of response and tests of such devices produce a frequency curve in the form of a substantially straight line with no drop-off of dip in the curve at the maximum frequency which

it is commercially possible to record on frequency test records at the present time. The tests of this device indicate that the invention is inherently capable of faithfully responding to frequencies far higher and lower than the frequencies which are recordable at the present time. This predetermined tension holds the armature in the same position for lateral operation allowing the free rocking motion of the armature to take place in operation with lateral cut records. The spring 23 is so shaped that its unloaded position is as shown in Fig. 4, and when in loaded or operative position the parts are disposed as shown in Figs. 1, 2 and 3 with the armature in neutral position both mechanically and electrically. With a thickness of spring to meet the above requirement, its width is substantially greater than its thickness. Very satisfactory results have been obtained with a width of the order of at least twenty times thickness and a length of the order of at least sixty-two times thickness; thus allowing easy flexing for vertical motion and easy torsional flexing for rocker motion, while presenting substantially infinite resistance against being pulled to either side bodily, thus preventing contact of the armature 14 with any of the poles N1—N2 and S1—S2. Accordingly, the stylus 24 is adapted to follow either a vertical or a lateral cut record and transform the groove undulations into mechanical motion which in turn modulates the magnetic field passing between the poles N1—N2 and S1—S2 and through the armature 14.

Two oppositely wound coils 26, 27, preferably identical in dimension, number of turns, and impedance, surround respectively corresponding branches of the pole pieces 12 and 13, as shown in Fig. 1 somewhat diagrammatically. This arrangement serves to transform the magnetic fluctuations resulting in the movement of the armature, into corresponding alternating electrical potentials in the manner to be more particularly pointed out following.

When it is desired to use the invention for vertical cut records the coil terminals 26b and 27a are connected together, and the coil terminals 26a and 27b are connected to a suitable receiving circuit, such as is well known to those skilled in the art and need not be further described. Assuming a vertical vibratory force to be applied to the stylus, as by the undulations on a vertical cut record, the following magnetic and consequent electrical action takes place. The armature 14 moves upward away from poles N1 and S1 and toward poles N2 and S2, thus reducing the magnetic flux between the poles N1 and S1 and increasing the magnetic flux between the poles N2 and S2 to the same extent due to the fact that the area of overlap between the armature 14 and the poles N1 and S1 decreases in the same ratio as the overlap with respect to the poles N2 and S2 increases. This induces an electrical potential in the coils 26 and 27. When the armature 14 moves downwardly, the flow of flux between the poles N1 and S1 is correspondingly increased and the flow between the poles N2 and S2 is decreased, inducing a potential of opposite polarity in the coils and thus completing the full alternation. The coils being connected in series boosting (for vertical motion of the stylus) provide double the voltage of either single coil. As will be understood by those skilled in the art, the coils may be connected in parallel boosting, which will also result in the current alternations of the coils being in phase for vertical movement of the stylus and

180° out of phase for lateral movement of the stylus.

With the coils connected as above described for vertical cut records, a lateral ancillary force applied in the lateral direction, say to the right, will move the point of the stylus 24 to the right, causing the right side of armature 14 to rise and the left side to move downwardly an equal distance, which will produce a change of flux in all of the 10 arms or branches of the pole pieces, increasing the flow of flux from N1 to S2 and decreasing the flow of flux from N2 to S1, thereby inducing a potential in both of said coils. However, with the terminals connected as above noted, the potentials 15 in the coils (resulting from lateral motion of the stylus) are 180° out of phase or bucking, thereby resulting in zero voltage between the terminals 26a and 27b. Similarly, lateral movement of the stylus in the opposite direction will likewise result 20 producing zero voltage between the terminals 26a and 27b.

When the device is to be used in connection with lateral cut records the terminal 26b is connected to the terminal 27b so that the potentials due to lateral movement of the stylus are additive or boosting; while the potentials resulting from ancillary vertical movement of the stylus are in bucking relationship and neutralize each other. Similarly, the coils may be connected 25 in parallel boosting for lateral motion of the stylus, by connecting terminals 26a and 27a to one branch of the receiving circuit and terminals 26b and 27b to the other branch of the receiving circuit.

30 A single coil may be used on any one of the four branches of the pole pieces in connection with other features of the invention. However, such a single coil cannot discriminate between flux variations caused by vertical or lateral motions of the armature and although the use of a single coil eliminates a switching operation when changing the connections between the terminals of the coils 26 and 27, more scratch noise is produced. As has been previously indicated, it has been found that the rough surface in the sound groove will actuate the stylus in both the vertical and lateral direction, i. e., on lateral cut records there are present ancillary vertical undulations and vice versa. Through the use of the two coil 35 arrangement the vertical scratch impulses are neutralized whenever the coils are connected for the reproduction of lateral cut records, and the lateral scratch impulses are neutralized whenever the coils are connected for the reproduction of vertical cut records. This is a distinct advantage as it improves the ratio of amplitude of scratch noise to music. Additionally, the use of two coils raises the efficiency of the pickup, and therefore such use is greatly preferable.

40 Referring to Fig. 2, it is evident that whether the armature 14 moves in either a vertical direction or in a rocker fashion the direction of flux flow is always from N1 and N2 to S1 and S2; and hence there is no reversal of flow through the armature 14. When a vertical signal displaces the armature, either up or down, no substantial change in the quantity of flux flow in the said armature takes place, as any decrease in flux coupling between the armature and N2 and S2 results 45 in an equal increase in flux coupling between N1 and S1, the sum total effect results in no flux variation in the said armature.

70 The term "flux coupling" is used to indicate that a variation in the quantity of flux flow between a given pair of poles of opposite polarity

is obtained by varying the overlapping or interleave area of armature coupling to said magnetic poles and not by the conventional reduction of the air gap distance between armature and pole.

For lateral reproduction, the rocking motion of the armature produces no substantial change in the quantity of flux flowing through the armature, for when the armature end adjacent poles N1 and N2 moves downward the said flux coupling to N1 decreases the same amount that it increases in flux coupling to N2, the same condition of course exists between the poles S1 and S2, the sum total effect resulting in no flux variation.

Because of the absence of flux reversals or variations, eddy currents and hysteresis do not exist, permitting a density of flux in the armature that imposes full saturation without impairing the fidelity of reproduction. This allows the reduction of the mass of material making it possible to extend the frequency range. In view of this it is within the contemplation of the invention to eliminate the magnet 10 (Fig. 1) and in its place transformer iron can be substituted and the armature then made of permanent magnet material. The fidelity will remain the same and the efficiency will be in proportion to the strength of the magnet material used.

Further reduction of weight in the armature is effected due to the fact that the efficiency is in no way influenced by how long or short the distance from N1 and N2 to S1 and S2 may be. It is therefore desirable to make the width and length of the armature as small as possible. However, the amplitude of the signal from lateral recordings depends upon the ratio of the distance from the point of the stylus 24 (Fig. 1) to the imaginary center C or rocking axis, to the distance from center C to either end that is adjacent the poles N1 and N2 or S1 and S2. By reducing the distance of the stylus point from the axis C to as short a length as mechanical facilities allow, the total length of the armature can be brought to where the above mentioned ratio is either 1 to 1 or a step up or step down ratio to suit application requirements, and have a total armature weight of a fraction of a gram. Fig. 3 shows the preferred relative proportions of the width of the armature 14 to its length.

Having thus described our invention with particularity with reference to a preferred embodiment thereof, and having referred to certain modifications, it will be obvious to those skilled in the art, after understanding our invention, that other changes and modifications may be made therein without departing from the spirit and scope of the invention, and we aim in the appended claims to cover such changes and modifications as are within the scope of the invention.

What we claim is:

1. In a pickup device of the magnetic type, the combination of a magnetic circuit including poles of opposite polarity and having parallel flux paths for each pole, each of said poles having upper and lower pole ends provided with spaced vertical coplanar faces, a first electrical coil surrounding one path of one pole and a second electrical coil surrounding a corresponding path of the opposite pole, said paths being so disposed with respect to each other as to provide parallel fields across which flux flows in the same lateral direction, and an armature having laterally oppositely disposed ends provided with vertical faces in spaced substantially parallel overlapping relationship with said coplanar vertical pole faces of opposite polarity respectively, said armature being supported intermediate its laterally dis-

posed ends for vibratile motion within the field of influence of both of said paths in continuous overlapping and substantially parallel spaced relationship.

2. In a sound translation device of the magnetic type, the combination of an armature supported for vibratile motion, a magnetic circuit including poles of opposite polarity having laterally extending coplanar vertical pole faces of opposite polarity providing a magnetic flux field comprising two flux paths in which said armature is adapted to vibrate in relatively opposite directions from a neutral position to thereby oppositely vary the flux strength of said armature having vertical surface areas disposed in spaced overlapping parallel relation with respectively corresponding vertical pole faces, said armature being supported about a laterally central axis with its oppositely disposed ends movable parallel to and in continuous flux coupling relation with respectively cooperating faces of said pole faces, a stylus secured to said armature for movement of said armature in said field responsive to a sound track record throughout its range of movement, and a signal generating circuit responsive to said armature vibrations.

3. In a sound translation device of the magnetic type, magnet means having pole pieces of opposite polarity each having upper and lower branches provided with coplanar pole faces, an armature provided with oppositely disposed ends adjacent respective pairs of said branches of opposite polarity, said oppositely disposed armature ends overlapping said vertical pole faces in parallel spaced relation therewith, said armature being supported for rocking motion about an axis disposed intermediate said poles of opposite polarity in a lateral direction and intermediate said upper and lower branches in a vertical direction, spring means supporting said armature in a vertical position relative to said pole branches when in operative position and providing for predetermined rocking movement about said axis in both directions, and providing for predetermined vertical movement and restraining said armature against bodily movement in a lateral direction, and an electrical circuit including a flux path through said armature.

4. In a sound translation device of the magnetic type, the combination of a plurality of pole pieces providing a pair of laterally disposed air gaps spaced vertically one from the other, means for supplying magnetic flux across said air gaps in the same direction of flow, said pole pieces having vertical coplanar faces, an armature in the field of influence of said flux supported from its central point for rocking motion in a plane substantially parallel to said coplanar pole faces about an axis extending substantially normal to the direction of flux flow across said gaps, said armature being movable also in a direction normal to said axis and being restrained against bodily movement in a direction parallel to said flux flow, said armature ends being provided with substantially vertical surface areas movable parallel to and spaced from respectively cooperating faces of said pole pieces, electrical circuit means including a magnetic flux field variable synchronously with the movement of said armature, and a mechanical motion translating element attached to said armature.

5. In a sound translation device of the magnetic type, the combination of magnetic pole pieces of opposite polarity having spaced coplanar vertical side faces, an armature having vertical

faces in parallelism with the respective vertical faces of said pole pieces in spaced overlapping relationship therewith, and a support for said armature limiting movement of said vertical faces within a plane substantially parallel to the faces of said pole pieces.

6. In a sound translation device of the magnetic type, the combination of an armature supported for rocking movement and for relatively vertical movement, a magnetic circuit including poles of opposite polarity having laterally extending coplanar vertical pole faces of opposite polarity providing a magnetic flux field within which said armature is movable in relatively opposite directions from a neutral position, said armature having vertical surface areas disposed in spaced overlapping parallel relation with respectively corresponding vertical pole faces, said armature being supported about a laterally central axis with its oppositely disposed ends movable parallel to and in continuous flux coupling relation with respectively cooperating faces of said pole faces, a stylus secured to said armature for movement with said armature throughout its said range of movement, and a signal generating circuit responsive to movement of said armature.

7. In a sound translation device of the magnetic type, magnet means having pole pieces of opposite polarity each having upper and lower branches, an armature provided with oppositely disposed ends adjacent respective pairs of said branches of opposite polarity, said ends and respectively adjacent pole branches being in spatial interleaved relationship providing clearance throughout the operating movement of said armature and providing relatively fixed air gaps and variable area coupling, said armature being supported for rocking motion about an axis disposed intermediate said poles of opposite polarity in a lateral direction and intermediate said upper and lower branches when in operative position in a vertical direction, spring means for supporting said armature in a vertical position relative to said polar branches and providing for predetermined rocking movement about said axis in both directions and providing for predetermined vertical movement and restraining said armature against bodily movement in a lateral direction, and an electrical circuit including a flux path through said armature.

8. In a sound translation device of the magnetic type, magnet means having pole pieces of opposite polarity each having upper and lower branches provided with coplanar vertical faces, an armature provided with oppositely disposed ends adjacent respective pairs of said branches of opposite polarity, said oppositely disposed armature ends having vertical surface areas overlapping corresponding of said pole faces in parallel spaced relation therewith, spring means for supporting said armature in a vertical direction relative to said polar branches and providing for predetermined rocking movement about said axis in both directions and providing for predetermined vertical movement and restraining said armature against movement in a lateral direction, said spring means being of such compliance as to maintain said armature constantly in said overlapping parallel spaced relationship during the full range of its operative movement, and an electrical circuit comprising at least one coil surrounding one of said pole branches.

9. In a sound translation device of the magnetic type, magnet means having pole pieces of opposite polarity each having upper and lower

branches provided with coplanar vertical faces, an armature mounted for bodily movement in an up and down direction and for rocking movement about an axis substantially normal to said

5 first direction of movement and restrained against movement of said axis laterally, said armature having oppositely disposed ends provided with vertical surface areas spaced outwardly from said axis and disposed adjacent respective pairs of 10 said branches of opposite polarity in spaced overlapping parallelism with said vertical pole faces, spring means supporting said armature in a vertical direction relative to said polar branches when in operative position and providing for predetermined 15 rocking movement about said axis in both directions and providing for predetermined vertical movement and restraining said armature against bodily movement in a lateral direction, and an electrical circuit including a flux path through said armature.

10. In a device of the character described, the combination of a magnetic circuit comprising pole members having pole ends of opposite polarity spaced apart to provide a magnetic field, said pole ends having laterally extending coplanar vertical pole faces an armature disposed in said field and provided with a member rigidly secured thereto for movement therewith, said armature having vertical surfaces overlapping corresponding of said pole faces in spaced parallelism therewith, stationary electrical coil means surrounding at least one of said pole members, and resilient means supporting said armature in continuous overlapping and substantially constant spaced 30 parallel relationship with said pole faces for predetermined vibratile motion in a vertical direction and for predetermined rocking motion and restraining said armature against bodily lateral movement, whereby said armature is maintained in flux coupling relationship and its movement effects flux modulation by variable area coupling.

11. In a device of the character described, the combination of a magnetic circuit comprising pole members having pole ends of opposite polarity spaced apart to provide a magnetic field, said pole ends having laterally extending coplanar vertical pole faces an armature disposed in said field and provided with a member rigidly secured thereto for movement therewith, said armature having vertical surfaces overlapping corresponding of said pole faces in spaced parallelism therewith, a plurality of stationary coils surrounding respective of said pole members of opposite polarity and providing means for supporting electrical 45 alternations to a receiving circuit, said coils being connected in boosting relationship for vertical movements of said armature and in opposing relationship for rocking movements of said armature, and resilient means supporting said armature for predetermined vibratile motion in a vertical direction and for predetermined rocking motion and restraining said armature against bodily lateral movement, whereby said armature is maintained in flux coupling relationship and its movement effects flux modulation by variable area coupling.

12. In a device of the character described, the combination of a magnetic circuit comprising pole members having pole ends of opposite polarity spaced apart to provide a magnetic field, said pole ends having laterally extending coplanar vertical pole faces, an armature disposed in said field and provided with a member rigidly secured thereto for movement therewith, said armature having 70 vertical surfaces overlapping corresponding of

11

said pole faces in spaced parallelism therewith, a plurality of stationary coils surrounding respective of said pole members of opposite polarity and providing means for supplying electrical alternations to a receiving circuit, said coils being connected in boosting relationship for rocking movements of said armature and in opposing relationship for vertical movements of said armature, and resilient means supporting said armature in continuous overlapping and substantially constant spaced parallel relationship with said pole faces for predetermined vibratile motion in a vertical direction and for predetermined rocking motion and restraining said armature against bodily lateral movement, whereby said armature is maintained in flux coupling relationship and its movement effects flux modulation by variable area coupling.

13. In a magnetic type pickup, the combination of a magnetic circuit including laterally spaced pole ends of opposite polarity having laterally extending vertical pole face areas arranged in coplanar relationship and providing a flux field including a laterally extending air gap disposed between spaced pole ends of opposite polarity, a vibratory armature disposed in said flux field and having substantially vertical face areas extending in substantial spaced parallelism to and overlapping said pole faces, a stylus rigidly secured to said armature, resilient supporting means for said armature, whereby upon movement of said stylus by a vertical cut record said armature is moved relative to said pole ends in a direction transverse to said flux flow while maintained in said substantial parallelism, and said armature ends are movable parallel to respectively cooperating faces of said pole ends.

14. In a magnetic type pickup, the combination of a magnetic circuit having oppositely disposed pole pieces provided with substantially vertical laterally extending coplanar pole faces constructed and disposed so as to provide two air gap flux paths across both of which flux flows in the same lateral direction and spaced apart in a relatively vertical direction, an armature having vertical face areas disposed in spaced parallel relationship with respectively corresponding of said pole faces, resilient means supporting said armature for differential movement relative to said flux streams in overlapping relationship with said coplanar pole faces whereby when said device is in operative position said armature lies in the path of both flux streams and is disposed in flux coupling relationship to said pole pieces

12

throughout its maximum operative movement, and said armature ends are movable parallel to respectively cooperating faces of said pole ends.

15. In a magnetic pickup the combination of a magnetic circuit providing a flux field including two spaced flux streams flowing in a lateral direction across an air gap defined by pole ends having substantially vertical coplanar pole faces, a vibratory armature having substantially vertical laterally oppositely disposed face areas, a stylus rigidly secured to said armature, and resilient means independent of said pole ends supporting said armature in operative neutral position with said armature disposed in said flux field in substantially magnetic equilibrium relative to said flux streams and with its said face areas spaced closely adjacent and in substantially parallel overlapping relationship with corresponding of said coplanar pole faces, said resilient supporting means guiding said armature during its vibratile movement and maintaining said spaced and substantially parallel overlapping relationship throughout the operative movement of said armature, whereby said flux is modulated by variable area coupling, and an electrical circuit responsive to said flux modulation.
